UNITED STATES PATENT OFFICE.

JAMES M. LEAVER, OF LONGBEACH, CALIFORNIA.

DRY-KILN FOR LUMBER.

1,039,301.

Specification of Letters Patent.

Patented Sept. 24, 1912.

Application filed July 10, 1911. Serial No. 637,805.

To all whom it may concern:

Be it known that I, JAMES M. LEAVER, a citizen of the United States, residing at Longbeach, in the county of Los Angeles and State of California, have invented a new and useful Dry-Kiln for Lumber, of which the following is a specification.

The invention relates to improvements in dry kilns for lumber.

10 The object of the present invention is to improve the construction of dry kilns, and to increase the efficiency of the same, and to provide a simple and comparatively inexpensive dry kiln, adapted to mix heated moist air from the kiln with cold air, which enters the kiln from the outside to raise the temperature of the incoming air, so that when the same strikes the steam pipes, it will be raised to a much higher temperature 20 than is obtainable under the ordinary drying processes where the cold air is either conducted directly to the steam pipes or simply passes through ducts, which are exposed to the heat of the kiln, or is subjected 25 to a preliminary heating by auxiliary steam coils.

A further object of the invention is to provide a dry kiln of this character, adapted 30 to afford perfect control of the degree of heat, the circulation of the air and the quantity of moisture in the kiln, and capable of being advantageously employed either in progressive systems of drying where one end 35 of the kiln is maintained at a higher temperature than the other, or in kilns for drying lumber in a batch or block, that is to say, the entire contents of the drying chamber containing a number of cars at one time.

With these and other objects in view, the 40 invention consists in the construction and novel combination of parts hereinafter fully described, illustrated in the accompanying drawings, and pointed out in the claims hereto appended; it being understood that 45 various changes in the form, proportion, size and minor details of construction, within the scope of the claims, may be resorted to without departing from the spirit or sacrificing any of the advantages of the 50 invention.

In the drawings:—Figure 1 is a vertical transverse sectional view of a dry kiln, constructed in accordance with this invention. Fig. 2 is a longitudinal sectional view on 55 the line 2—2 of Fig. 1. Fig. 3 is a longitudinal sectional view of the upper portion

of the kiln on the line 3—3 of Fig. 1. Fig. 4 is a horizontal sectional view on the line 4—4 of Fig. 1. Fig. 5 is a horizontal sectional view on the line 5—5 of Fig. 1. Fig. 6 is a transverse sectional view, illustrating another form of the invention, and taken substantially on the line 6—6 of Fig. 13. Fig. 7 is a transverse sectional view, taken substantially on the line 7—7 of Fig. 11. Fig. 8 is a transverse sectional view on the line 8—8 of Fig. 10. Fig. 9 is a longitudinal sectional view of a portion of the dry kiln on the line 9—9 of Fig. 8. Fig. 10 is a longitudinal sectional view on the line 10—10 of Fig. 8. Fig. 11 is a horizontal sectional view on the line 11—11 of Fig. 7. Fig. 12 is a horizontal sectional view, taken substantially on the line 12—12 of Fig. 6. Fig. 13 is a horizontal sectional view, taken substantially on the line 13—13 of Fig. 6.

Like numerals of reference designate corresponding parts in all the figures of the drawings.

The dry kiln illustrated in Figs. 1 to 5 inclusive of the accompanying drawings comprises in its construction side walls 1 and 2, and a roof 3, all of which may be constructed of any suitable material. The dry kiln, which may be constructed in a series, as indicated in Fig. 1, may of course be made with a single drying chamber 4, and it is provided at the top of the same with a ceiling or top wall 5, spaced from the roof 3 and composed of oppositely inclined side 80 portions, as clearly illustrated in Fig. 1 of the drawings, but I do not wish to limit myself to an oppositely inclined top wall or ceiling, as any other preferred arrangement may be employed, and it may be constructed 85 of any suitable material. The intervening space between the top wall or ceiling 5 and the roof 3 is divided by inclined longitudinally disposed partitions 7 into a lower mixing chamber 8 and upper suction chambers 90 9. The partitions 7, which may be made of any preferred construction, extend from the opposite side walls of the kiln to the center of the underside of the roof, and their outer side edges are located slightly above the side 100 edges of the top wall or ceiling of the drying chamber and provide openings 10 and 11 for connecting the mixing chamber with vertical cold air inlet ducts 12 and vertical 105 down ducts 13, which connect the mixing 110 chamber with transverse bottom ducts or passages 14. The vertical cold air inlet

ducts are formed in the side walls 1, which are provided at the lower portions of the vertical ducts 12 with air inlet openings 15, the passage of the air through the openings 15 being controlled by a hinged damper 16, or other suitable means. The cold air is caused to travel upwardly through the vertical inlet ducts or passages by the suction in the chambers 7 with which stacks 17 and 18 communicate, the area of the stacks being sufficiently in excess of the area of the inlet openings to produce the desired draft through the passages or ducts, whereby a positive damper controlled circulation of air 15 through the kiln is produced. The walls are preferably made hollow, as shown, and consist of inner and outer shells and studding 19, arranged at intervals and dividing the space between the inner and outer shells 20 into ducts or passages and forming dead air spaces between the passages. The top wall or ceiling is preferably supported by studding 20 to the underside of which the top wall or ceiling is suitably secured, and the said top 25 wall or ceiling supports substantially V-shaped deflectors 21, located opposite the openings 10 and adapted to deflect the air entering the mixing chamber in order to produce a uniform distribution of the same. 30 The deflectors present angularly disposed faces to and are adapted to split the current of air passing upward through the ducts or passages 12. The cold or incoming air after entering the mixing chamber commingles 35 with warm moist air, which is introduced into the mixing chamber 8 through vents 22 in the top wall or ceiling. These vents, which are preferably arranged at intervals at the ridge of the top wall or ceiling, may 40 be located at any desired points, and they preferably consist of short ducts, tapered upwardly and extending into the mixing chamber from openings in the top wall or ceiling. The draft through the kiln causes 45 the air from the mixing chamber to travel downwardly through the ducts or passages 13 to the lower transversely disposed ducts or passages 14, which are provided with outlets 23, preferably located centrally of the space between the rails 24 of the tracks of the kiln. When the kiln is arranged in multiple or series, the wall 2 dividing the members of the multiple kiln will contain the 50 down passages 13 and also the cold air ducts 25 of the adjacent member of the multiple kiln, the ducts 13 and 25 being arranged at suitable points, as indicated in Figs. 4 and 5 of the drawings. The rails 24 of the tracks are supported upon standards or posts 26 55 in the usual manner, and the kiln is equipped with heating pipes 27, located above the lower transverse air passages or ducts 14 and supported by transverse beams 28, or other suitable means and preferably consisting of longitudinally disposed steam pipes.

but the steam or heating pipes may be arranged in any preferred manner, as may be readily understood. The air passing upward through the outlet openings of the lower transverse passages or ducts impinges 70 against the heating pipes, and its temperature is raised by the latter to a much higher degree than is possible when cold air taken immediately from the outside atmosphere is directed against the heating pipes, and as it 75 is moist by the admixture of a portion of the air of the drying chamber of the kiln, it possesses greater advantages than highly heated dry air, it being a well recognized fact that a certain amount of moisture must be maintained in the kiln in order to keep the surface of the lumber soft and the pores open to prevent warping, checking, hollow horning, case hardening and other injurious results. Moisture may be supplied to the kiln 80 by injecting live steam or exhaust steam into the same, or by any other suitable means, and as this is well known in the art and does not constitute a portion of the present invention, illustration thereof is deemed unnecessary. The kiln may be constructed of any desired capacity, and in the accompanying drawings it is shown with two tracks for the reception of kiln cars 29 upon which the lumber or other material to be dried is 85 loaded. In order to direct the hot air toward the center of the lumber at the bottom, the kiln is equipped with central and side deflectors 30 and 31, extending longitudinally of the kiln and located centrally 90 of the spaces between the tracks and at the side walls 1 and 2. The deflectors are located approximately in the plane of the tracks and the heating pipes, and the central deflector 30 is substantially triangular 95 in cross section and presents to the rising air inclined side faces 32, which diverge upwardly and are adapted to deflect the air toward the median line of the cars and the contents thereof. The side deflectors 31 100 have inclined inner side faces 33, which extend upwardly and inwardly for directing the rising air toward the center of the material at the bottom of the same. The central and side bottom deflectors at this point 110 are preferably made hollow, as shown, but they may be constructed in any preferred manner. The kiln is also equipped at the upper portion with inclined deflectors 34, located in the angles formed by the side 115 walls and the top wall or ceiling and extending downwardly and inwardly and adapted to re-direct the rising air into contact with the material at the outer sides thereof. The kiln is provided at intervals 120 with outlet suction devices 35, depending at intervals from the top wall or ceiling of the kiln, and designed to be located at suitable intervals beneath the ridge of the said top wall or ceiling and tapered downwardly. 130

The depending suction ducts 35 are connected at their upper ends with the suction chambers 9 by opposite transverse branch ducts or passages 36, arranged at an inclination and extending upwardly and outwardly in opposite directions from the centrally arranged outlet suction ducts to the partitions 7, and communicating at their outer ends with the suction chambers 9 through suitable openings in the said partitions. The outlet suction ducts are equipped at their lower ends with suitable dampers 37 for controlling the escape of the moist air from the drying chamber, and thereby regulating the temperature of the same and the moisture contained therein. The dampers 37, which are of the butterfly type, may be of any construction and any suitable operating mechanism may be employed for adjusting the dampers. In the drawings, they are mounted on suitable pivots or pintles 38, having crank arms 39 to which rods 40 are connected. The suction chambers 9, which extend substantially the entire length of the kiln, are connected at their ends with the hooded stacks or chimneys 17 and 18 by means of suitable damper controlled outlets 41 and 42, located directly beneath the said stacks or chimneys 17 and 18. The stack or chimney 18, which is twice the capacity of the stack or chimney 17, is divided by a central partition 43 to form two passages 44 and 45, which are connected at their lower ends with the adjacent kiln members, as clearly illustrated in Fig. 1 of the drawings. The dampers 46 for controlling the passage of air from the suction chambers to the stack are hinged at 47 and are designed to be operated by any suitable means. By adjusting the dampers of the chimneys, the strength of the draft and the consequent circulation of air through the kiln is controlled, and this in connection with the control of the temperature and moisture of the drying chambers through the dampers of the outlet suction ducts will enable the kiln to be employed for the progressive drying of lumber, or for the simultaneous drying of the entire contents of the kiln. The kiln is also provided at each end with an upper transverse chamber or duct 48, extending downwardly from the roof to the plane of the side edges of the top wall or ceiling, and provided below the intermediate portion of the ceiling with suitable damper controlled outlet openings 49 to permit the moist air to pass directly from the drying chamber through the said transverse end chambers or ducts 48 to the chimneys or stacks. This will enable more complete control of the heat and moisture to be obtained, and the damper 50 for controlling the passage of air through the opening 49 is hinged at the top and may be operated by any suitable means. The ends of the dry-

ing chamber 4 are closed by suitable doors 51, which may be of any preferred construction.

In Figs. 6 to 13 inclusive of the drawings is illustrated another form of invention, in which the dry kiln comprises in its construction side walls 52, a roof 53, and a top wall or ceiling 54 composed of inclined side portions, extending upward from the side walls at points below the roof 53 to a point beneath the center or median line thereof and forming upper longitudinal mixing chambers 55. The mixing chambers 55, which receive heated air and vapor from the drying chamber 56 through vents 57, are located adjacent to the ridge of the top wall or ceiling 54 and consist of openings formed in the inclined portions of the same. The incoming air from the exterior of the dry kiln enters through lower longitudinal ducts 57*, having lateral branches 58 and containing auxiliary heating pipes 59 for raising the temperature of the cold air, as it enters the kiln. The longitudinal cold air ducts are located beneath the floor 60, and the lateral branches, which are located at suitable intervals, connect the longitudinal cold air ducts with vertical ducts or passages 61, arranged within the side walls 52 of the kiln and connected at their upper ends with upper inclined ducts or passages 62, disposed transversely of the inclined side portions of the top wall or ceiling and extending upwardly from the side edges thereof across the same to within a short distance of the ridge and provided at their upper ends with outlet openings 63, communicating with the mixing chambers 55, as clearly illustrated in Fig. 6 of the drawings. The kiln is equipped at the upper ends of the inclined transversely disposed ducts or passages 62 with approximately V-shaped deflectors 64, having angularly disposed sides or wings and arranged to split and deflect the currents of air for distributing the same uniformly throughout the mixing chambers, and to cause the incoming air to commingle thoroughly with the heated air and moisture of the drying chamber of the kiln. The mixing chambers 55 are also connected by down ducts or passages 65 with lower transverse ducts or passages 66, located within the floor 67 and having outlet openings 68, arranged centrally beneath the space between the rails 69. The outlet openings 68 extend through the floor 67, which also preferably constitutes the top wall of the longitudinal cold air duct 57*. The lower transverse air ducts are provided at the inner sides of the outlet openings 68 with inclined partitions 70, which assist in directing the air through the openings 68. The rails of the tracks are supported upon standards or posts 71, and the main heating pipes 72 are arranged substantially the same

as the heating pipes 27 heretofore described, being supported by transverse beams 73. The preliminary heating of the air by the auxiliary steam pipe 59 and the admixture 5 with the thus heated air with the hot moist air from the drying chamber enables the temperature of the air entering the drying chamber to be raised to a comparatively high degree by the main heating pipes 72, 10 as will be readily understood. The dry kiln is equipped at the bottom above the main heating pipes with central and side deflectors 74 and 75, constructed substantially the same as those heretofore described. The 15 central deflector 75 is triangular in cross section, and presents upwardly diverging side faces before directing the air to the material contained on the kiln cars 76. The side deflectors 75, which are mounted upon 20 the side walls of the kiln, are approximately V-shaped in cross section and have inclined sides, which extend upwardly and inwardly for directing the heated air toward the material under treatment. Upper deflectors 77 25 constructed similar to the upper deflectors 36 are provided for also directing the air toward the material and to prevent a free passage of air upward through the space between the lumber and the side walls of 30 the kiln. The deflectors 77, which are disposed longitudinally of the kiln, extend downwardly and inwardly at the angles formed by the side walls and the inclined portions of the top wall or ceiling. The hot 35 air and moisture from the drying chamber pass out to the chimneys or stacks 78 and 79 through outlet suction ducts 80, arranged vertically in the side walls 52 of the kiln and having lower openings 81 and upper 40 openings 82. The suction outlet ducts are arranged at intervals throughout the length of the side walls of the kiln, and the lower openings communicate with the drying chamber, and the upper openings are in communication with the longitudinal suction 45 chambers 83, located at opposite sides of the kiln above the outer portions of the top wall or ceiling and at the outer sides of the mixing chambers 55. The stacks or chimneys, 50 which communicate with the suction chambers at the ends thereof, have sufficient area to cause a positive circulation of air through the passages of the kiln, and the draft and the consequent escape of the heated air and 55 moisture are controlled by suitable dampers 84, arranged at the lower portions of passages 85, which connect the suction chambers with the chimneys or stacks. The dampers are preferably pivotally mounted, 60 the pivots or pintles being provided with exterior crank arms 86 to which rods 87 are connected.

The dry kiln may be arranged in a series of multiples, as indicated in the accompanying drawings, and each kiln or mem-

ber is distinct from the others, and the circulation, temperature and moisture are under complete control through the adjustment of the dampers 84 of the chimneys or stacks.

So far as I am aware it is new to mix in a chamber or duct cold air from the outside atmosphere with heated moist air from the drying chamber before the cold air is introduced under the heating pipes.

Having thus fully described my invention, what I claim as new and desire to secure by Letters Patent, is:—

1. A dry kiln including a drying chamber, a mixing chamber or duct located at the top of the kiln, means for conducting the air from the outside atmosphere to the mixing chamber or duct, means contained within the kiln for mixing a portion of the heated moist air with the cold air to cause the same to commingle in the mixing chamber before the air from the outside atmosphere is introduced into the drying chamber, means for conducting the mixture from the mixing chamber or duct to the drying chamber, and heating means located within the kiln and arranged in the path of the said mixture, and a chimney or stack communicating with the drying chamber for producing a circulation through the kiln.

2. A dry kiln including a drying chamber, a mixing chamber located above the drying chamber, separate ducts connecting the mixing chamber with the outside atmosphere and with the lower portions of the drying chamber, means contained within the kiln for introducing a portion of the heated moist air of the drying chamber into the mixing chamber to cause the same to commingle with the cold air before the latter is introduced into the drying chamber, and heating means located within the drying chamber and arranged in the path of the air entering the same.

3. A dry kiln including a drying chamber, a mixing chamber, separate means for connecting the mixing chamber with the outside atmosphere and with the drying chamber, means contained within the kiln for mixing a portion of the heated moist air of the drying chamber with the cold air to cause the same to commingle in the mixing chamber before the air from the outside atmosphere is introduced into the drying chamber, a chimney or stack, and a suction chamber connected with the drying chamber and with the chimney or stack for conveying away the heated air and moisture.

4. A dry kiln including a drying chamber, a mixing chamber communicating with the drying chamber and adapted to receive heated air and moisture from the same, ducts connecting the mixing chamber with the outside atmosphere and with the drying chamber at the bottom thereof, heating

- means located within the drying chamber in the path of the air entering the same, and a suction chamber connected with the drying chamber, a chimney or stack connected with the suction chamber for conveying away the heated air and moisture and for causing a draft or circulation through the kiln, and means for controlling the draft through the stack or chimney.

5. A dry kiln including a drying chamber, a mixing chamber located above the drying chamber and communicating therewith so as to receive heated air and moisture therefrom, separate ducts connecting the mixing chamber with the outside atmosphere and with the drying chamber, means for heating the air entering the drying chamber, a suction chamber also located above the drying chamber and connected therewith, and a chimney or stack communicating with the suction chamber.

6. A dry kiln including a drying chamber, a mixing chamber located at the top of the kiln, means for connecting the mixing chamber with the outside atmosphere, ducts located at the bottom of the drying chamber and having outlets communicating therewith, means for connecting the ducts at the bottom of the drying chamber with the mixing chamber, means contained within the kiln for introducing a portion of the heated moist air of the drying chamber into the mixing chamber to cause the same to commingle with the cold air before the latter is introduced into the drying chamber, and heating means located within the drying chamber and arranged in the path of the air entering the same.

7. A dry kiln including a drying chamber, a mixing chamber located at the top of the kiln, means for connecting the mixing chamber with the outside atmosphere, ducts located at the bottom of the drying chamber and having outlets communicating therewith, means for connecting the ducts at the bottom of the drying chamber with the mixing chamber, means contained within the kiln for introducing a portion of the heated moist air of the drying chamber into the mixing chamber to cause the same to commingle with the cold air before the latter is introduced into the drying chamber, heating means located within the drying chamber and arranged in the path of the air entering the same, and deflectors located above the heating means for directing the air upon the material to be dried.

8. A dry kiln including a drying chamber, a mixing chamber communicating with the drying chamber and adapted to receive heated air and moisture from the same, means for connecting the mixing chamber with the outside atmosphere, ducts arranged at the bottom of the drying chamber and having outlet openings for discharging air into the same, means for connecting the bottom ducts with the mixing chamber, heating means located within the drying chamber in the path of the air entering the same, side deflectors located at opposite sides of the drying chamber and having upwardly and inwardly inclined faces, and a deflector located between the side deflectors and having upwardly diverging side faces.

9. A dry kiln including a drying chamber, a mixing chamber communicating with the drying chamber and adapted to receive heated air and moisture from the same, means for connecting the mixing chamber with the outside atmosphere, ducts arranged at the bottom of the drying chamber and having outlet openings for discharging air into the same, means for connecting the bottom ducts with the mixing chamber, heating means located within the drying chamber in the path of the air entering the same, tracks located above the heating means, and deflectors arranged between the tracks and at the outer sides thereof for directing the heated air toward the material.

10. A dry kiln including a drying chamber, a mixing chamber communicating with the drying chamber and adapted to receive heated air and moisture from the same, means for connecting the mixing chamber with the outside atmosphere, ducts arranged at the bottom of the drying chamber and having outlet openings for discharging air into the same, means for connecting the bottom ducts with the mixing chamber, heating means located within the drying chamber in the path of the air entering the same, tracks located above the heating means, a central deflector located at the space between the tracks and having upwardly diverging inclined side faces, and side deflectors located at the outer sides of the tracks and having upwardly and inwardly extending inclined faces.

11. A dry kiln including a drying chamber, a mixing chamber communicating with the drying chamber and adapted to receive heated air and moisture from the same, means for connecting the mixing chamber with the outside atmosphere, ducts arranged at the bottom of the drying chamber and having outlet openings for discharging air into the same, means for connecting the bottom ducts with the mixing chamber, heating means located within the drying chamber in the path of the air entering the same, tracks located above the heating means, a central deflector located at the space between the tracks and having upwardly diverging inclined faces, and inclined deflectors located at the upper portion of the drying chamber and extending from the side walls thereof for directing the heated air against the material.

12. A dry kiln including a drying chamber

- ber, a mixing chamber communicating with the drying chamber and adapted to receive heated air and moisture from the same, means for connecting the mixing chamber 5 with the outside atmosphere, ducts arranged at the bottom of the drying chamber and having outlet openings for discharging air into the same, means for connecting the bottom ducts with the mixing chamber, heating 10 means located within the drying chamber in the path of the air entering the same, tracks located above the heating means, a central deflector located at the space between the tracks and having upwardly diverging inclined faces, lower deflectors arranged between the tracks and at the sides thereof and having inclined faces for directing the heated air against the material to be dried, and upper deflectors located at opposite sides of the drying chamber and having inclined faces arranged to direct the heated air against the material.
13. A dry kiln including opposite side walls, a roof, a top wall or ceiling forming 25 a drying chamber, an upper mixing chamber, means contained within the kiln for introducing a portion of the heated moist air of the drying chamber into the mixing chamber, vertical ducts arranged in the side 30 walls and communicating at their upper ends with the mixing chamber, one of the ducts being connected at its lower portion with the outside atmosphere and the other duct communicating with the drying chamber at the bottom portion thereof, and heating means arranged within the drying chamber in the path of the air entering the same.
14. A dry kiln including opposite side walls, a roof, a top wall or ceiling forming 40 a drying chamber, and an upper mixing chamber communicating with the drying chamber and adapted to receive heated air and moisture from the same, vertical ducts arranged in the side walls and communicating 45 at their upper ends with the mixing chamber, one of the ducts being connected at its lower portion with the outside atmosphere and the other duct communicating with the drying chamber at the bottom portion thereof, heating means arranged within the drying chamber in the path of the air entering the same, a suction chamber located at the upper portion of the kiln and communicating with the drying chamber, and a chimney or stack connected with 50 the suction chamber.
15. A dry kiln including opposite side walls, a roof, a top wall or ceiling forming 60 a drying chamber, and an upper mixing chamber communicating with the drying chamber and adapted to receive heated air and moisture from the same, vertical ducts arranged in the side walls and communicating at their upper ends with the mixing
- chamber, one of the ducts being connected 65 at its lower portion with the outside atmosphere and the other duct communicating with the drying chamber at the bottom portion thereof, heating means arranged within the drying chamber in the path of the air 70 entering the same, a suction chamber located above the top wall or ceiling and extending longitudinally of the kiln, and suction ducts arranged at intervals and connecting the suction chamber with the drying 75 chamber.
16. A dry kiln including opposite walls, a roof, a top wall or ceiling forming a drying chamber and an upper mixing chamber located above the drying chamber, a vertical duct located at the side of the drying chamber and communicating at the lower end with the outside atmosphere and at the upper end with the mixing chamber, a deflector arranged for splitting and spreading 80 the current of air entering the mixing chamber, means for introducing heated air and moisture from the drying chamber to the mixing chamber, and means for connecting the mixing chamber with the heated portion 85 of the drying chamber.
17. A dry kiln including side walls having vertical ducts, a roof, a top wall or ceiling forming a drying chamber and an upper mixing chamber located above the drying 90 chamber and communicating therewith to receive heated air and moisture therefrom, means for connecting the upper ends of the vertical ducts with the mixing chamber, means for connecting the lower ends of some 95 of the vertical ducts with the outside atmosphere, and means for connecting the lower ends of the other vertical ducts with the bottom portion of the drying chamber for discharging air into the same, and heating 100 means arranged in the path of the air discharged into the drying chamber.
18. A dry kiln including side walls having vertical ducts, a roof, a top wall or ceiling forming a drying chamber and an upper mixing chamber located above the drying chamber and communicating therewith to receive heated air and moisture therefrom, means for connecting the upper ends of the vertical ducts with the mixing chamber, means for connecting the lower ends of some 110 of the vertical ducts with the outside atmosphere, means for connecting the lower ends of the other vertical ducts with the bottom portion of the drying chamber for 115 discharging air into the same, heating means arranged in the path of the air discharged into the drying chamber, a longitudinal suction chamber also located above the top wall or ceiling, and outlet suction ducts or passages arranged at intervals and connecting the drying chamber with the suction 120 chamber.

19. A dry kiln including side walls having vertical ducts, a roof, a top wall or ceiling forming a drying chamber and an upper mixing chamber located above the drying chamber and communicating therewith to receive heated air and moisture therefrom, means for connecting the upper ends of the vertical ducts with the mixing chamber, means for connecting the lower ends of some of the vertical ducts with the outside atmosphere, means for connecting the lower ends of the other vertical ducts with the bottom portion of the drying chamber for discharging air into the same, heating means arranged in the path of the air discharged into the drying chamber, longitudinal suction chambers located at opposite sides of the kiln and arranged above the top wall or ceiling, outlet suction ducts arranged at intervals and connecting the drying chambers with the suction chambers, and chimneys or stacks located at the ends of the kiln and connected with the ends of the suction chambers.
20. A dry kiln including opposite walls, a roof, a top wall or ceiling connected with the side walls and forming a drying chamber and spaced from the roof, a longitudinal partition dividing the space above the top wall or ceiling into a suction chamber and a mixing chamber, the mixing chamber communicating with the drying chamber and adapted to receive heated air and moisture therefrom, means for connecting the mixing chamber with the outside atmosphere and with the drying chamber, and separate means for connecting the drying chamber with the suction chamber, and a chimney or stack connected at the bottom with the suction chamber.
21. A dry kiln including opposite walls, a roof, a top wall or ceiling connecting the side walls to form a drying chamber and spaced from the roof, longitudinal partitions dividing the space above the top wall or ceiling into opposite suction chambers and a mixing chamber, the latter communicating with the drying chamber and adapted to receive heated air and moisture therefrom, means for connecting the mixing chamber with the outside air and with the drying chamber, and an outlet suction duct depending from the top wall or ceiling and having branches connected with the opposite suction chambers.
22. A dry kiln including opposite walls, a roof, a top wall or ceiling connecting the walls to form a drying chamber, partitions located above the top wall or ceiling and forming opposite suction chambers and a mixing chamber, a vent connecting the mixing chamber with the drying chamber, ducts connecting the mixing chamber with the outside atmosphere and with the drying chamber, and an outlet suction device depending from the top wall or ceiling and having branches connected with the opposite suction chambers.
23. A dry kiln including a drying chamber, a mixing chamber communicating with the drying chamber and adapted to receive heat and moisture therefrom, ducts for connecting the mixing chamber with the outside atmosphere and with the drying chamber, a chimney or stack, a suction chamber communicating with the chimney or stack and connected with the drying chamber, and damper controlled means for directly connecting the drying chamber with the chimney or stack.
24. A dry kiln including a drying chamber, a mixing chamber communicating with the drying chamber and adapted to receive heat and moisture therefrom, ducts for connecting the mixing chamber with the outside atmosphere and with the drying chamber, chimneys or stacks, opposite longitudinal suction chambers located above the drying chamber and communicating with the chimneys or stacks, outlet suction ducts connecting the suction chambers with the drying chamber, and upper transverse ducts arranged at the ends of the suction ducts and communicating with the drying chamber and the chimneys or stacks to permit the heated air and moisture to pass directly to the said chimneys or stacks, and means for controlling the passage of air through the ducts or chambers.
25. A dry kiln including a drying chamber, heating pipes at the bottom thereof, a mixing chamber or duct, passages for conveying cold air from the outside atmosphere to the mixing chamber or duct, means contained within the kiln for introducing heated moist air from the drying chamber into the mixing chamber or duct to cause the same to commingle with the cold air before the latter is introduced into the drying chamber, separate means for conducting air from the mixing chamber to a point beneath the heating pipes, and a chimney or stack communicating with the drying chamber for causing a circulation through the kiln.
26. A dry kiln including a drying chamber, heating means, a mixing chamber or duct, a passage for conducting cold air from the outside atmosphere to the mixing chamber or duct, means contained within the kiln for mixing a portion of the heated moist air of the drying chamber with the cold air and for causing the same to commingle in the mixing chamber before the air from the atmosphere is introduced into the drying chamber, separate means for conducting the mixed air from the mixing chamber or duct to the drying chamber, and a chimney or stack communicating with the

drying chamber for causing a circulation through the kiln.

27. A dry kiln including a drying chamber, a mixing chamber arranged at the top 5 of the drying chamber, a suction chamber also located at the top of the drying chamber and extending along the kiln and communicating with the said drying chamber, a passage for conducting cold air from the 10 outside atmosphere to the mixing chamber, means contained within the kiln for mixing a portion of the heated moist air of the drying chamber with the cold air and for causing the same to commingle in the mixing 15 chamber before the air from the outside at-

mosphere is introduced into the drying chamber, separate means for conducting the mixed air from the mixing chamber to the drying chamber, means for heating such cold air, and a chimney or stack connected with 20 the suction chamber for causing a circulation through the kiln.

In testimony that I claim the foregoing as my own, I have hereto affixed my signature in the presence of two witnesses.

JAMES M. LEAVER.
